UNITED STATES PATENT OFFICE.

DAVID HAMMOND AND W. R. REEVES, OF CANTON, OHIO.

IMPROVEMENT IN BRIDGE-GIRDERS.

Specification forming part of Letters Patent No. 43,202, dated June 21, 1864.

To all whom it may concern:

Be it known that we, DAVID HAMMOND and W. R. REEVES, both of Canton, in the county of Stark and State of Ohio, have invented a new and useful Improvement in Wrought-Iron Trussed Girders for Bridges and Other Structures; and we do hereby declare that the following is a full, clear, and exact description thereof, which will enable others skilled in the art to make and use the same, reference being had to the accompanying drawings, forming a part of this specification, in which—

Figure 1 is a side view of a bridge. Fig. 2 is a plan of the same. Fig. 3 is a transverse vertical section of the same. Figs. 4 and 5 are transverse sections of one of the two girders of which the bridge is composed.

Similar letters of reference indicate like parts.

This invention consists in a novel construction of a wrought-iron arch and novel combination of an arch and string-piece, suspension-rods, and diagonal braces, whereby we obtain a girder of great strength and stiffness with a comparatively small weight.

The arch A of each girder is composed of three continuous pieces, *a a b*, of flat bar-iron, of which two, *a a*, are set up edgewise opposite each other and at a distance apart equal to the thickness of the suspension-rods B B and diagonal braces C C, and the third, *b*, is laid down over the upper edges of *a a* and secured thereto at suitable distances by wrought or cast iron clamping-pieces *c c*, screw-bolts *d d*, and nuts *e e*.

The clamping-pieces consist of plates of iron notched or grooved in their upper sides, as shown in Fig. 5, to receive and fit the lower edges of the bars *a a*, under which they are placed. The bolts *d d*, having their heads downward, pass through holes in the said clamping-plates and holes in the top piece, *b*, of the arch, as shown in Fig. 4, and are secured by the nuts *e e* being screwed onto them above the top piece, *b*. The string-piece D is also composed of a continuous straight piece of flat bar-iron set up edgewise and arranged to form a chord to the arch A, to the ends of which it is secured by being placed between the pieces *a a* and having bolts or rivets *h* inserted through the whole. The said string-piece and arch are

also connected together at suitable distances by the suspension-rods B and diagonal braces C, which are placed between the pieces *a a* of the arch. The rods and braces are made of flat bar-iron, and their upper ends are finished off in the form of screw-pins which pass through holes in the piece *b*, and are secured by nuts *f f* above the arch. The upper parts of the said rods and braces are further secured to the arch by screw-bolts or rivets *g g*, inserted through them and through the pieces *a a*. The lower parts of the said rods and braces are made of hook form, as shown in Fig. 3, the hook-formed portions receiving within them and supporting the string-piece, and being clamped thereon by screw-bolts or rivets *i i*, inserted through them and the string-piece. The arch-girder thus constructed has its ends fitted and supported in cast-iron shoes E E, so formed as to support the arch against any tendency to longitudinal extension. These shoes are secured to the arch and string-piece by making the bolts *h h* pass through them as well as through the arch and string-piece. The string-piece, being firmly secured to the ends of the arch, acts as a tension-brace to prevent the elongation of the arch. The two or more of these girders of which a bridge is composed are braced transversely in any suitably manner. The roadway is supported upon transverse timbers F F, placed across and resting on the string-pieces E E, but its weight is transferred to the arch by the supporting-rods B B and braces C C, the latter also bracing the arch.

What we claim as our invention, and desire to secure by Letters Patent, is—

1. The arch constructed of the side pieces, *a a*, top piece, *b*, clamping-pieces *c c*, bolts *d d*, and nuts *e e*, the whole combined substantially as herein specified.
2. The combination of the arch constructed as hereinbefore specified, the string-piece D, suspension-rods B B, diagonal braces C C, and shoes E E, substantially as herein specified.

DAVID HAMMOND.
W. R. REEVES.
